ABSTRACT OF THE DISCLOSURE

A bracket for holding a street light or sign is composed of upper and lower members connected by triangular side plates spot welded at spaced points to the upper and lower members to form a tapered structure adapted to be secured to a post.

This invention relates to a bracket for holding a street light or sign.

Lightweight street light brackets are ordinarily composed of tapered aluminum tubes which are produced by spinning a large diameter cylindrical aluminum work-piece. This requires the use of expensive spinning equipment.

The object of this invention is to produce a hollow lightweight tapered bracket of pleasing appearance which is sufficiently strong for holding a light or a sign, and the making of which does not require the use of expensive spinning equipment.

In general, this object is obtained by forming a bracket of an upper member joined to a lower member by means of triangular side plates. These plates are welded to the members by spot welds which are alternately spaced along the length of the side plate. The location of the welds together with the plates gives a truss-like construction which is of pleasing appearance, is adequately strong, and is inexpensively fabricated.

Alignment rods are placed in grooves in the outer end portion of the bracket for facilitating the assembly of the bracket.

The means by which the objects of the invention are obtained are described more fully with reference to the accompanying drawings in which:

FIGURE 1 is a front elevational view of the bracket;
FIGURE 2 is a cross-sectional view taken on line 2—2 of FIGURE 1;

FIGURE 3 is a cross-sectional view taken on the line 3—3 of FIGURE 1; and

FIGURE 4 is a cross-sectional view taken on the line 4—4 of FIGURE 1.

The bracket is composed of an upper member 10, a lower member 12 and a pair of triangular side plates 14 and 16. The upper and lower members are respectively downwardly and upwardly concave and preferably substantially semi-cylindrical, and except for the outer end portion 18 are inclined with respect to each other. The base end portion 19 includes the triangular side plates 14 and 16. Each side plate has beveled edges 20 which are seated in corresponding grooves 22 in longitudinal edges on the upper and lower members 10 and 12, respectively.

The side plates are secured to the upper and lower members by means of spot welds alternately spaced along the longitudinal length of the side plates. Welds 24 and

2

26 are on the interior wall surface of the bracket while welds 28 and 30 are on the outside surface of the bracket. As these welds are alternately spaced on the upper and lower members, they form a triangular path which resembles a truss construction. The use of spot welds rather than continuous welds reduces the weight of the bracket.

In the outer end portion 18 starting at the position for weld 30, the edges of both the upper and lower members 10 and 12 are provided with grooves 31. Alignment rods 32 are seated in these grooves to keep the outer end portions aligned during assembly. The free end of the bracket is secured by spot weld 34 located inside the bracket, this weld joining the upper member 10 to the lower member 12.

15 The bracket is mounted on a base plate 40 having an oval rib 42. The base end of the bracket is seated within the rib 42 and joined thereto by means of a weld 44.

The completed bracket can then be secured to either a wood or metal pole 50 by means of one or more bolts 20 52. An opening 54 is in the bottom of lower member 20 for the passage of electric wires. A street light or sign can be hung on the end portion 18 by any conventional means.

Having now described the means by which the objects 25 of the invention are obtained,

I claim:

1. A bracket adapted to be attached to a pole for holding a light or a sign comprising an upper downwardly concave member, a lower upwardly concave member, a pair of triangular side plates, beveled edges on said plates, grooves in said upper member and said lower member coextensive with said plates and into which said beveled edges are seated, alignment grooves in the edges of the outer end portions of the upper member and the lower member, alignment rods seated in said alignment grooves for forming a joint between said upper member and lower member, first spot welds alternately spaced on said upper member and said lower member and along said plate joining each member to the plates, and second spot welds directly connecting the upper member to the lower member along said alignment rods.

2. A bracket as in claim 1, said first and second spot welds being alternately placed on the inner and outer surfaces of said bracket.
